US00D534403S

(12) **United States Design Patent** (10) **Patent No.:** **US D534,403 S**
Concari (45) **Date of Patent:** **** Jan. 2, 2007**

(54) **DRILL**

(75) Inventor: **Gabriel E. Concari**, Eldersburg, MD
(US)

(73) Assignee: **Black & Decker Inc.**, Newark, DE
(US)

(**) Term: **14 Years**

(21) Appl. No.: **29/211,122**

(22) Filed: **Aug. 11, 2004**

Related U.S. Application Data

(63) Continuation-in-part of application No. 29/204,243, filed on Apr. 27, 2004, now Pat. No. Des. 500,653, which is a continuation of application No. 29/197,251, filed on Jan. 13, 2004, now Pat. No. Des. 497,786.

(57) **CLAIM**

The ornamental design for a drill, as shown and described.

DESCRIPTION

FIG. 1 is a front perspective view of a drill showing my new design.

FIG. 2 is a front elevational view of the drill of FIG. 1.

FIG. 3 is a rear elevational view of the drill of FIG. 1.

FIG. 4 is a right side elevational view of the drill of FIG. 1.

FIG. 5 is a left side elevational view of the drill of FIG. 1.

FIG. 6 is a top plan view of the drill of FIG. 1; and,

FIG. 7 is a bottom plan view of the drill of FIG. 1.

The broken lines and the areas within the broken lines are for illustrative purposes only and form no part of the claimed design.

1 Claim, 7 Drawing Sheets
